CONTROL DEVICE

Ludwig Treubert, Dresden, Germany, assignor
to General Electric Company, a corporation of
New York

Application May 19, 1938, Serial No. 208,943
In Germany June 25, 1937

2 Claims. (CL. 201—48)

This invention relates to control devices, more particularly to step by step control devices such as manually operated starting switches for electric motors, and has as its object simple and reliable means for holding the movable member of the device in any one of several positions and for returning said member to a starting position in the event of failure of voltage.

In one form, the invention consists of a voltage drop release device for step by step switches or the like wherein the switch shaft is provided with an electromagnetically operated brake which normally holds the shaft in a desired position against the tension of a spring. In the event of failure of the voltage supply, the electromagnet of the brake is deenergized and the switch is thrown to an off position by the spring. Moreover, the holding force of the brake is regulated in dependence upon the position of the switch so that the braking force is just sufficient to overcome the force supplied by the spring. This braking force can be overcome by the operating means for the switch so as to move the switch to a different desired position.

For more complete understanding of the invention, reference should be had to the accompanying drawing, Fig. 1 of which is an enlarged fragmentary view mostly in section showing an electromagnetic brake applied to a rotary motor starting switch in accordance with this invention, while Fig. 2 is a wiring diagram showing a rotary starting switch having the construction of Fig. 1 connected to control an electric motor.

Referring to the drawing, the invention is shown as applied to a motor starting and speed regulating switch consisting of a control arm 10 secured to a shaft 11 which is rotatably mounted in a bearing provided for it in a supporting plate or base 12 preferably made of electrically insulating material. On the base 12 are a plurality of concentric arcuate contacts or arcuate series of contacts consisting of an inner solid ring 13, an outer circular row of spaced contacts 14 terminating in a solid contact 15, a third concentric solid contact 16 and a plurality of contacts 17 and a fourth solid contact 18. The switch arm 10 is provided with sliding contact members electrically connected to each other and respectively engaging and making electrical contact with the concentric contacts as the switch arm is moved over them.

In the operation of this control switch, the arm 10 is moved during the starting operation in a clockwise direction, its longer end 19 start-

ing from the off position indicated by the insulated segments 20. With the connections shown in Fig. 2 in the circuit of an electric motor, the supply switch 21 being closed, the switch arm 10 first completes a circuit for the field winding 22 of the motor through the contact 16 and the switch arm to the inner contact 13, which is connected to one side 21a of the supply source. Also the circuit for the armature 23 of the motor is established from the contact 13 through the switch arm to some one of the contacts 14 and through starting resistances (not shown) connected across the contacts 14 through the contact 15 to the armature of the motor. As the arm is turned farther, the resistance in the armature circuit of the motor is cut out to bring the motor up to speed until the segment 15 is reached. The field circuit of the motor is unchanged until the switch arm 10 reaches the contacts 17 thereby inserting in the field circuit resistances (not shown) connected across these contacts whereby the field strength and hence speed of the motor are regulated.

Referring to Fig. 1 in accordance with the invention, the lower end of the switch arm shaft 11 is provided with a disc 24 which is splined to the shaft 11 so as to be movable a short distance axially of the shaft. This disc is provided with a beveled friction brake surface 25 on its upper side which fits in the beveled end of a cylindrical member 26 secured by a screw 27 to the support 12. In order to provide a flux path for the brake magnet coil 28, the cylindrical member 26 and the disc 24 are made of magnet core iron. The coil 28 surrounds the shaft 11 but is preferably secured to the cylindrical member 26 so as to be stationary. By means of a helical spring 29 surrounding the cylindrical member 26, the shaft 11 is biased to its off position, movement of the switch arm 10 from the off position winding up the spring 29.

As shown in Fig. 2, the brake coil 28 is preferably energized just before and during the time that the switch arm 10 is in its regulating position in engagement with some one of the contacts 17. As shown, the coil 28 is connected to the conducting contact 18 and has its other terminal connected directly to the supply conductor 21b. It is thus arranged so that when the switch arm 10 reaches the contact 18, the coil 28 is connected directly across the supply source through the contact arm 10 to the segment 13 and therefore, the brake coil 28 acts as a zero voltage coil.

When the coil 28 is energized, the disc 24 is drawn by the coil to bring its beveled brake sur-

face into engagement with the similar surface on the cylindrical member 26 with sufficient force to hold the switch arm 10 against the return force supplied by the spring 29. Thus the switch arm is secured in that position. Also the braking force is not great enough to prevent further movement of the switch arm in either direction as desired, the switch arm being forceably moved against the action of the brake. Preferably the contact segment 18 acts as an electrical resistance to regulate the energization of the coil 28, and thereby the brake force, in proportion to the increase in force applied by the spring 29 as the switch is advanced in such a manner that the braking force at all times is just sufficient to hold the switch arm in place against the spring. If desired, the segment 18 may be in the form of a series of contacts corresponding to the contacts 17 with resistances connected between them.

20 In the event of failure of the supply source voltage the coil 28 is deenergized and releases the brake whereupon the spring 29 returns the switch arm 10 to its starting position. Also the same action obviously takes place in the event that the switch 21 is opened to stop the motor.

What I claim as new and desire to secure by Letters Patent of the United States is:

1. A motor starting and speed regulating control device comprising a movably mounted control member, a spring biasing said control member to a predetermined starting position, electric contact means in the path of movement of said control member from said starting position to an intermediate position, motor armature starting resistance means connected electrically to said contact means, means on said control member engaging said contact means to cut out said resistance for starting of a motor during movement of said control member to said intermediate position, speed regulating contact means arranged in the path of said control member from said intermediate position to a final position, motor field regulating resistance means connected to said speed regulating contact means, means carried by said control member cooperating with said speed regulating contact means to insert said field regulating resistances in the field circuit of a motor in moving from said intermediate position to said final position and thereby regulate the speed of the motor, a pair of brake members having engaging frictional surfaces, means securing one of said brake members to said control member, supporting means securing the other of said brake members against movement, a coil arranged when energized to hold said brake members into engagement with each other, brake resistance contact means in the circuit of said coil arranged in the path of movement of said control member between said intermediate and said final positions, means carried by said control

member cooperating with said brake resistance contact means to close the circuit of said coil when said control member is moved to said intermediate position and thereafter to vary the energization of said coil so as to increase the frictional engagement between said brake members with increase in the force applied to said control member by said spring as said control member is moved toward said final position and thereby hold said control member in any position on said speed regulating contact means.

2. A motor starting and speed regulating control device comprising a pivotally mounted control member, a spring biasing said control member to a predetermined starting position, a series of contacts in the path of movement of said control member from said starting position to an intermediate position, motor armature starting resistances connected electrically between said contacts, means on said control member engaging said contacts to cut out said resistance for starting of a motor during movement of said control member to said intermediate position, a series of speed regulating contacts arranged in the path of said control member from said intermediate position to a final position, motor field regulating resistances connected between said speed regulating contacts, means carried by said control member cooperating with said speed regulating contacts to insert gradually said field regulating resistances in the field circuit of a motor in moving from said intermediate position to said final position and thereby regulate the speed of the motor, a pair of brake members having an annular engaging frictional surfaces in concentric relation with the axis of said control member, means securing one of said brake members to said control member, supporting means securing the other of said brake members against movement, a coil arranged when energized to hold said brake members in engagement with each other, brake regulating resistance means in the circuit of said coil arranged in the path of movement of said control member between said intermediate and said final positions, means carried by said control member cooperating with said brake regulating resistance means to close the circuit of said coil through said brake regulating resistance means when said control member is moved to said intermediate position and thereafter to vary said brake regulating resistance means and thereby vary the energization of said coil so as to increase the frictional engagement between said brake members with increase in the force applied to said control member by said spring as said control member is moved toward said final position and thereby hold said control member on any one of said speed regulating contacts.
